United States Patent Office

Des. 191,172
Patented Aug. 22, 1961

191,172

TOY FIGURE

Lenore H. Morgan, 2601 Manor Drive, Midland, Mich.

Filed Apr. 6, 1961, Ser. No. 64,643

Term of patent 14 years

(Cl. D34—4)

FIG. 1 is a front elevational view of the toy figure embodying my new design, and

FIG. 2 is a side elevational view.

I claim as my invention:

The ornamental design for a toy figure, substantially as shown.
